MATCH BOOK DISPLAY STAND

Joseph Shapiro, St. Louis, Mo.

Application July 10, 1950, Serial No. 11,039

Term of patent 3½ years

(Cl. D80—9)

To all whom it may concern:

Be it known that I, Joseph Shapiro, a citizen of the United States, residing at the city of St. Louis, State of Missouri, have invented a new, original, and ornamental Design for a Match-Book Display Stand, of which the following is a specification, reference being made to the accompanying drawing, forming a part thereof, in which

I claim:

The ornamental design for a match-book display stand, substantially as shown.

JOSEPH SHAPIRO.
